SWITZERLAND.

STAMPING MACHINE.

Application filed August 20, 1923. Serial No. 658,419.

To all whom it may concern:

Be it known that we, EDUARD GEISTLICH, JULES RAST, FRITZ KUMMER, and FRITZ PAULI, all citizens of Switzerland, and residents of Lucerne, Switzerland, have invented a new and useful Improved Stamping Machine, of which the following is a specification, and for which we have filed applications in Switzerland on November 27, 1922, 10 and in Germany on January 9, 1923.

This invention relates to a stamping machine apt to produce perfect imprints of artistic appearance and being suited to form a complete substitute for postage stamps and 15 the like. The machine is provided with an inking device which applies the ink so carefully that the finenesses and niceties of the clichés, the use of which the invention renders possible, are distinctly reproduced.

20 Among the stamps to be imprinted there is also one without a value-stating number, that stamp being intended for trial imprints; all stamps bearing value-stating numbers, as well as other stamps, are so arranged on an adjustable carrier and connected with counting devices for the imprints that on printing any stamp with value number not only a totalizing counting device is thrown into gear, but also a special or separate counting device pertaining to that special value stamp, whereas in the case of 25 printing stamps without value numbers or the like all counting devices are thrown out of gear.

30 Our invention is illustrated by way of example in the accompanying drawings, in which Figure 1 is a side view of our improved machine. Figure 2 shows some details of the inking device in vertical section and drawn on an enlarged scale. Figure 3 is a plan of the parts shown in Figure 2. Figure 4 is a side view of some details of the 35 drive. Figure 5 is a plan of some details of the means for throwing the counting devices into, and out of, gear, and for locking them.

40 Figure 6 is a side view of the parts shown in Figure 5, in locking position. Figure 7 is also a plan of some details of the counting device gear. Figure 8 is a side view of some 45 details relating to the means for operating the printing table. Figure 9 is a side view of some details relating to the means for actuating the inking device. And Figure 10 is a side view of some details relating to the 50 ink supply roller gear.

The printing stamps 7 which are formed by clichés bearing, generally, a value-stating number are arranged around a rotary adjustable carrier 6, the stamp 7^a which bears no value number and serves merely for 60 trial imprints being the last of the circular series. The adjustment of the rotary carrier in such a manner that a definite stamp lies just opposite to the printing table 8 is effected by an adjusting lever 2 which is turnable on a shaft 2^a and is in gear, by means of a cogged sector 5, with a cog-wheel secured to the shaft of the carrier 6. The lever 2 can be coupled with a sector 4 having recesses 4^a and being affixed to the frame of the machine, the coupling being effected by means of a pawl 3 attached to said lever. The notches 4^a are so spaced that each space is equivalent to any one of the spaces between the stamps 7 on the rotary carrier 6. 65

At the other end of the lever 2, near its pivot, is provided a short toothed sector or cogged bevel wheel part 9 meshing with a bevel wheel 10 and rotating it so much by the lever 2 that that counting device 13 is 70 thrown into gear which pertains to the stamp located at the time being above the table 8. The respective counting device is thrown into gear by means of a cog-wheel 11 secured to the lower end of the shaft of the 75 bevel-wheel 10 and meshing with circumferential cogs provided on a shiftable shaft 12 which is shifted in correspondence with the extent of movement of the lever 2 so that a lateral projection 14 provided at the shaft 12 80 arrives below a lever 15 of the counting device concerned, there being, as many such devices as there are value stamps in the machine, as may be judged from Figures 5 and 7. No counting device is, however, provided 85 for the trial stamp 7^a, as also already explained. 90

Hinged to the lever 2 is a rod 16, the free end of which is formed as a rack whose teeth mesh with a pinion secured to a shaft 17 100 supported in movable arms 20 hinged to a shaft 57. The shaft 17 is provided with as many pins 18 as there are counting devices, and are distributed along and around their shaft 17 in a spiral arrangement, any one of the pins resting on the feeler head 19 of the appertaining counting device. There is this condition as regards the projections 14 and the levers 15 on one side and the pins 18 and the feeler heads 19 on the other side that the 105 110

pin directed downwardly at the time being, and being, consequently, in operative position, pertains to that feeler head and that counting mechanism, which can be actuated 5 by means of its lever 15 and the shiftable projection 14.

Between each feelerhead 19 and the ap- 10 pertaining pin 18 is located a lever 56 which is also hinged to the shaft 57. The free end of each lever 56 is bent upwards in order to prevent collision between the feeler heads and the pins 18 when the counting de- 15 vices are thrown into gear. Both the pins 18 and their shaft 17 check the driving de- 20 vice of the machine when a counting device has run out. In this case the feeler head of the respective counting device disappears in the casing thereof, the shaft 17 and the arm or lever 56 which bears on the feeler 25 head of the respective counting device sink, and simultaneously therewith a safety pin 21 attached to the arm 20 is lowered and blocks the way for, or path of, a rod 22, Fig. 6. This rod is shifted by means 30 of a key 23 which is turnable on the axle 23^a and must be shifted every time a print is being made. When the way for, or path of, the shiftable rod 22 is free, the key 23 can be depressed (Fig. 1).

30 The machine may be operated in known manner, either by hand, or by mechanical means. In the example shown hand drive is chosen. The driving shaft 1 is rotated by means of a hand crank 1^a and is turned 35 twice in order to make one imprint. The revolution of the shaft 1 is transmitted to another shaft 26 by cog-wheels in the ratio 2:1, the shaft 26 making, thus, one revolution whilst an imprint is produced. The 40 shaft 1 is provided with a locking device which can be released only by the depression of the key 23. Attached to the shaft 26 are three cams, of which one, 51, controls the movement of the table 8 in the direction to 45 the cliché 7; the other, 38, controls the movement of the inking roller 44, and the third 27, controls the step motion of the roller 36 which takes the ink from the ink container.

50 The locking device, Fig. 4, consists of a disk 48 having a recess into which a pawl 24 may enter under the action of a spring (not shown), this spring acting on the key lever 23 which is connected with the pawl 24 by a bar 28. At the side of the disk 48 is another disk 25 provided with a nose, and being drawn by a spring against an abutment of the disk 48, the arrangement being such that said nose moves forward over the 55 recess by a small angle. The pawl 24 is as broad as both disks together and retains the disk at its nose counter to the action of the spring mentioned so that the recess of the disk 48, as well as the nose of the 60 disk 25, push upon the pawl in question, after it has engaged the recess provided for its reception. When the pawl 24 is lifted by means of the key 23, the disk 25 springs forward under the action of the spring provided for this purpose, and the 65 pawl remains lifted upon the circumference of the disk also after the key has been released; the circumference of the disk 25 at the point concerned is equal to the circumference of the disk 48. The hand 70 crank 1^a can now be turned, the pawl 24 gliding then on the circumference of the disk 48. The pawl 24 forms a bell-crank lever, and on its second arm 24^a acts a lever 47 which is connected with the device 75 for inking the clichés, the connection being such that in that moment in which the disks 48 and 25 have nearly completed the first rotation cannot drop into the recess of the disk 48 but remains lifted, whereas 80 while the second rotation is made the lever 47 releases the pawl 24^a so that its arm 24, after completion of the second rotation, locks again the disks 48 and 25, until another release is effected by a depression of 85 the key 23.

85 The control of the table 8 by means of the cam 51 is effected in that this cam lifts or lowers, as the case may be at the time being, a lever 55 carrying said table and being freely turnably carried by a shaft 55^a. The cam acts on said lever by the intermediary of another lever 53 hinged to the lever 55 and being provided at its free end with a roll 52 running on the cam 51, a coiled 90 spring 54 being inserted between the two layers, as shown in Figure 8. Owing to this arrangement and combination of parts, in connection with a rubber cushion attached to the table 8, the pressure under which the 95 imprints are made is particularly soft and the imprints are perfectly clean and clear and distinct, in fact, faultless.

95 The control of the inking roller 44 by means of the cam 38, Fig. 9, is effected by a 100 system of levers and links 39, 40, 41, 42, and 43, Fig. 9. Secured to the shaft 46 are, besides the levers 41 and 42, by which this shaft is turned, also a lever 47 by which the 105 pawl 24 is prevented from engaging the recess of the locking disk 48 after the first rotation of the driving shaft 1 has been completed. The lever 43 which carries the inking roller 44 is subjected to the pressure of a flat spring and touches, at the commencement of its movement, the roller 36 which takes the ink from the receptacle 37. When the system of levers, etc., 39, 40, 41, and 42, is moved by the cam 38 the inking roller 44 is 110 moved from the ink supply roller 36 along the bottom surface 45 of the ink receptacle or container 37 whereby the ink carried along by the roller 44 is rubbed and finely 115 distributed. The bottom surface 45 is plane 120 disk 25, push upon the pawl in question, in the example shown in Figure 1, but it 125

may be slightly curved. The position of the bottom surface 45 relatively to the cliché carrier 6 is such that it lies flush with the lowest cliché which is in position for printing. The inking roller 44 passes from the surface 45 to that cliché and is guided between the said bottom surface and the respective cliché by rollers 44^a, which are shown in Figure 3, and by ledges 58, of which one is shown in Figure 1, these rolls and ledges co-operating to guide the roller 44 to, and away from, the respective cliché.

The ink supply roller 36 is so arranged in the ink-receptacle 37 that it forms a closure therefor. It is controlled by a cam 27, Fig. 10, and by levers and links 29, 30, 31, 32, 33, and 34, in such a manner that at each rotation of said cam a pawl 35 attached to the link or arm 34 acts on a ratchet wheel 35^a secured to a shaft 36^a and causes the inking roller to make a part rotation corresponding to one tooth or to several teeth, as the case may be, whereby a certain definite amount of ink is conveyed from the receptacle or container 37 to the inking roller 44.

The oscillations of the lever 42 by which the inking roller is turned are transmitted to the shaft 12 by a link 49 and a lever 50. The shaft 12 is that provided with the projections 14 which act on the lever 15 of the individual counting devices (Fig. 7). The lever 50 sits loosely on the shaft 12 but is coupled therewith by a longitudinal groove provided in this shaft, and by a projection extending from the lever 50 into said groove and forming a kind of feather, the arrangement being, thus, such that the shaft 12 can be shifted longitudinally in the eye part of the lever 50 but this latter remains stationary, the rocking motions being, however, transmitted by the feather and the groove mentioned. The shaft 12 makes only part rotations in one and the other direction, or rocking motions respectively, and that projection 14 which is located below a lever 15 of a counting device, whichever it may be at the time being, operates the respective counting device by 1, that is to say, to enhance the number by 1. Also the rod 59 by which the totalizer 60 is actuated may be connected with a suitable part of a controlled motion, for instance with the arm 55 carrying the printing table 8. The rod 59 may be suspended, for instance, by the intermediary of a pivot from a member 55^b connecting the two arms of the double-lever 56 and pushes on the gear lever of the appertaining counting device when the arms 55 are swung upwards. If the cliché 7^a which bears no value number is adjusted by the gear lever 2, the shaft 12 is shifted into its end position and throws out of gear, firstly, all individual counting devices 13 by means of the noses

14 (Fig. 7), secondly, also the totalizing counting device 60 by means of the nose 74^a 65 which turns the rod 59 in such a manner that it no more contacts with the gear lever of the totalizing counting device.

We claim:

1. A stamping machine, comprising, in combination, a plurality of clichés adapted to produce imprints representing various definite values; a table adapted to receive the object which is to receive the imprints, and means to press said table elastically 70 against the cliché located above it; an inking roller for the respective cliché; and a corresponding number of individual counting devices for the various values and the imprints made as regards them, substantially as set 75 forth.

2. A stamping device, comprising, in combination, a definite plurality of stamps adapted to produce imprints bearing value signs; an ink-receptacle; an intermittently 85 acting ink transferring member; an intermittently acting gear adapted to cause said member to take a definite amount of ink out of said receptacle at each printing procedure; a plurality of counting devices for the 90 various imprints made and corresponding to the various values the imprints show, substantially as set forth.

3. A stamping machine, comprising, in combination, a plurality of clichés adapted 95 to produce imprints representing values; an ink container for said clichés; a roller adapted to convey a certain amount of ink from said receptacle at each imprint; another roller adapted to transfer an equal 100 amount of ink from said first-mentioned roller to the cliché which is in printing position, and a member having a rubbing surface so located as to be adapted to co-operate with said second roller; and a corresponding 105 plurality of counting devices for the various imprints and being so arranged as to be actuated singly, substantially as set forth.

4. A stamping machine, comprising, in combination, a plurality of clichés adapted 110 to produce imprints bearing value signs; an ink receptacle, the bottom of which forms a rubbing surface; an inking roller adapted to move over said surface and to convey ink from said receptacle to the cliché which is 115 in printing position; means to convey ink from the said receptacle to said roller; and a plurality of counting devices adapted to be actuated singly corresponding to the cliché adjusted for printing and being actuated 120 whilst the print is made, substantially as set forth.
